FIG. 1

FIG. 2

FIG. 3

FIG. 4

FIG. 5

FIG. 1 is a perspective view of a section of a beam for elevated railway showing my new design, it being understood that the broken lines are for illustrative purposes only;

FIG. 2 is a side elevational view thereof to a reduced scale;

FIG. 3 is a top plan view thereof to a reduced scale;

FIG. 4 is a bottom plan view thereof to a reduced scale; and

FIG. 5 is a typical end elevational view thereof.

The crossing pattern shown in the generally rectangular areas on the bottom of the claimed design in FIGS. 1 and 4 is understood to be continuous throughout said areas.

I claim:

The ornamental design for a beam for elevated railway, substantially as shown and described.
